UNITED STATES PATENT OFFICE.

EMIL A. CHRISTOPH, OF CHICAGO, ILLINOIS, ASSIGNOR, BY DIRECT AND MESNE ASSIGNMENTS, TO THE KING LOCK COMPANY, OF CHICAGO, ILLINOIS, A CORPORATION OF ILLINOIS.

LOCK.

1,204,410.

Specification of Letters Patent. Patented Nov. 14, 1916.

Application filed October 17, 1913. Serial No. 795,662.

To all whom it may concern:

Be it known that I, EMIL A. CHRISTOPH, a citizen of the United States, residing at Chicago, in the county of Cook and State 5 of Illinois, have invented certain new and useful Improvements in Locks, of which the following is a description.

My invention belongs to that general class of devices known as locks, and relates particularly to a key controlled or key actuated locking device of the kind described.

The invention has among its objects the production of a lock that cannot be easily picked, or one for which a key cannot easily 15 be made; in fact with the device herein described, instead of the key being made to fit the lock, the lock is made to fit its key. In constructing the lock, the desired number of similar keys for the lock are prepared, 20 and the lock parts then constructed to fit these keys, as herein described, so that only the key for which the lock is made will unlock that particular lock.

The invention has among its objects the 25 production of a device in which there is practically no limit to the possible variations or number of different keys, so that only one particular lock can be opened by the one set of keys, except, of course, in the 30 case where more than one lock is made to fit the same key.

The invention has among its further objects the production of a device of the kind described that is simple, compact, convenient, durable, efficient, and satisfactory, that may be economically manufactured, that may be used wherever found applicable, and modified in its non-essential details to make it applicable for different types or styles of 40 locks.

To this end my invention consists in the novel construction, arrangement and combination of parts herein shown and described, and more particularly pointed out in the claims.

In the drawings, wherein like reference characters indicate like or corresponding parts, Figure 1 is a sectional view of a device taken substantially on line 1, 1 of Fig. 50 4; Fig. 2 is a view of the key shown in Fig. 1, representing one form of key; Fig. 3 is a similar view of the opposite side, representing one design for that side; Fig. 4 is substantially a sectional view taken on line 55 4, 4 of Fig. 1; Fig. 5 is a view of the locking

mechanism shown in Fig. 1, with the key removed from the lock; Fig. 6 is a side elevation of a portion of a lock with a key inserted, showing the same before the plates have been fitted to the key and coöperating parts of the lock; Fig. 7 is substantially a 60 sectional view on line 7, 7 of Fig. 6; Fig. 8 is a perspective view of one form of plate; Fig. 9 is a similar view of another form; Fig. 10 is a similar view of still another form; Fig. 11 is substantially a sectional view of the key taken on line 11, 11 of Fig. 3; Fig. 12 is a front view of the centering plate 35; Figs. 13, 14 and 15 are cross sectional views, illustrating modifications of 70 the key, and Figs. 16 and 17 are side elevations of keys, illustrating modifications.

Referring to the drawings, in which one form of my device is shown, 1 represents a key of any suitable size. The key is provided with a plurality of irregular or undulated faces, forming substantially a plurality of what might be termed cam faces, or series of cam faces. The key shown has an irregular or undulated top face 2, and with a preferably parallel face 3 (see Fig. 11). It is also provided with a suitably formed groove 4 upon one side, having parallel sides 5 and 6, and on the opposite side is provided a bead 7, having longitudinal parallel faces 8 and 9. It may be mentioned at this time that the groove and bead may be extended along the key in any desired manner, and they need not extend parallel with each other, nor parallel with the top face 2; in fact they preferably do not so extend. A plurality of plates, each having a suitable aperture therethrough, are arranged to coöperate with the key faces. In Fig. 9 the plate shown consists of a plate 10 of preferably thin sheet metal provided with an aperture 11 therethrough, the ends of which are arranged to coöperate with the faces 2 and 3 of the key. The aperture is made of sufficient width to admit the key, that is, it is equal in width to the thickness of the key. The plate 15 shown in Fig. 10 is provided with a bead 16, having faces 17 and 18 adapted to extend in the slot 4 and coöperate with the faces 5 and 6 respectively. The plate 19 shown in Fig. 8 is provided with an aperture having a notch 20 on one side, and faces 21 and 22 for coöperation with the bead 7 of the key. These three forms of plate shown are, of course, merely for illus- 113

tration, as the particular form and size of apertures through the plates, depend, of course, upon the form of key; likewise, the apertures are not located in the same place on all the plates, as will be more fully understood from the further description. Where the bead 7 is omitted from the key, the plate 19 is not used, and similarly where the notch or groove 4 is omitted, plate 15 is not used, and if the edges 2 and 3 are straight and not undulated, plate 10, in some cases, is not used.

The plates are arranged face to face in any desired order, except, however, the beads 16 are all at one side, and the notches 20 at the other side, and the parts positioned in what may be termed a plate retaining member 23. The retaining member 23 is preferably cylindrical in form, and is provided with an opening or slot 25 therethrough, as most clearly shown in Figs 4 and 7. It will be noted by referring particularly to Figs. 1, 4 and 7, that the slot 25 is unobstructed, and extends entirely through the member from approximately one end toward the other end, and is connected by a suitable opening with the front of the lock. At the front end is provided a centering plate 35, formed substantially as shown in Fig. 12, but in which the opening depends upon the key used. The extreme end of the key is arranged to center in the end of part 23, as indicated at 36 in Fig. 1. The member 23 is formed with an extended part 24, and arranged within a coöperating lock or casing part 26, as will be hereafter described.

Before being fitted to the lock the plates described are substantially as shown in Figs. 6 and 7. Referring to these two figures, it will be noted that the plates are longer than the diameter of the part 23, so that they project beyond the face of the member. In fitting the lock to the key, the desired number and forms of plates are positioned in the slot 25 in member 23, and the key then inserted. The key passes through all the apertures in the plates, but owing to the irregular faces coöperating with the operative faces of the plates, slides them back and forth until when the key is in final position, the plates are substantially in the position shown in Fig. 6. The key being in place, the ends of the plate members are then suitably cut off, preferably flush with the face of the member 23, so that when the key is in, they are substantially contained within the member, as shown in Fig. 1. They may be cut off in any desired manner, either by turning, grinding, or the like, as indicated by the dotted lines at 36 in Figs. 6 and 7.

The coöperating part of casing 26 is provided with a cylindrical bore of a size to closely fit the member 23 and the plates as shown in Fig. 4. The same is also grooved

or formed with recesses at 29 and 30. When the parts are assembled, as shown in Fig. 1, with the key in position, one of the parts may be moved relative to the other, as for example, part 23 may be rotated in part 26, and this movement may be employed in any desired manner for controlling or operating the locking mechanism or latch bolt.

The member 23 may be secured in place in the casing 26 in any desired manner. In the drawings I have shown a plate 28, to which the extended part 27, or casing 26, is secured, and the end 24 of the part 23 is shown provided with a finger 33, which is adapted to engage a lock or latch part 34, or the equivalent. When the key 1 is withdrawn, the several plates in the slot 25, actuated by the different key faces, slide back and forth in the slot, or slots, permitting the key to be withdrawn. This, however, positively throws the various plates out of alinement, and beyond the face of the member 23 at one or both sides (i. e., positively disturbs them) so that they engage with the part 26 in the recesses or grooves 29 and 30. Their weight may be sufficient to cause them to drop down and engage in only one opening, as in the opening 29, depending, of course, on the manner of installation of the lock. However, if any do remain as left by the key, as for example as shown in Fig. 5, they will engage in the groove 30 and lock the member 23 against action. When the key is again inserted, they slide back and forth in the slot, depending, of course, upon the contour of the key and plates employed, until the key reaches its final position, at which point all of the members are alined at their ends, as indicated in Figs. 1 and 4, and are flush and conform to the contour of the member 23. This permits member 23 to be moved or rotated, permitting the latch to be turned, or positively turning it, depending upon the lock upon which employed. In inserting or withdrawing the keys, the movement of each plate is determined by the kind of plate used, and the particular form of key. It may be noted that with the type of key shown, plates all similar to 15, or all similar to 10, or all similar to 19, as the case may be, may be employed, or the same may be mixed, that is, varied in arrangement in any desired manner. When a lock is constructed in this manner, in order to bring all the plates in alinement, some must be moved in one direction and maintained in a particular position, and some moved in the opposite direction, and maintained there, depending upon the key employed. Very slight variations in the keys, owing to the required nicety of alinement of the plates, affords many different locks.

In Figs. 13, 14 and 15 several other forms of keys are shown. In Fig. 13, key 38 is

substantially wedge-shaped; in Fig. 14 the same is further modified in contour, and is shown provided with two grooves, each one of which may be employed to control a different series of plates; and in Fig. 15, the key 40 is similarly formed, so as to control more than one series at each side of the key. In the key shown in Fig. 16, the body-part 41 is provided with a groove 43 upon one side, and with a straight bead 42 upon the other. This straight bead 42 centers the key so that it is inserted, and may be moved longitudinally without any transverse movement. The key shown in Fig. 17 illustrates 10 a tapered form of key, also a tapered bead on one side. It is not considered necessary to show the plates that may be employed with these keys, as this will be obvious from the preceding. It might be mentioned that 15 if the plates 15, shown in Fig. 10, were formed with beads 16 of different lengths, this series of plates will be substantially subdivided into a sub-series, all of which will be controlled by the same bead on the key, 20 or *i. e.*, the same cam faces. The same is true with the plate 19, shown in Fig. 8, except, of course, the width of the aperture will be increased in a portion of the plates, giving the same result. These plates may all 25 be stamped out in quantity, each having the desired contour of aperture, and in assembling a lock, the plates may be mixed as may happen, without any particular order or system, placed in the slot, the desired key inserted, and then all of the plates turned 30 down. This obviates the expensive milling of an intricate key barrel, or plate retainer.

Owing to the considerable number of parts which must be fitted and alined to release 35 the lock, it may be safely said that the lock is practically unpickable, and likewise it is an extremely difficult task to fit a key to the lock bar unless every plate is alined or brought flush with the retaining part, so as 40 to clear the co-operating part of the lock, the retaining part being non-turnable. As a matter of fact it is an exceedingly difficult, if not impossible task, to rearrange the plates in their proper positions in the retaining 45 member if they are removed and intermixed, as endless combinations may be made in which the key would not aline all the plates to release the lock. For this reason it is desirable and economical when additional keys 50 are required, or when all the keys have been lost, to remove the retaining member and plates entirely and fit a new cylinder, keys and plates to the lock.

From the preceding description it will be 55 seen that, in the construction shown, the lock comprises a plurality of parts, one movable relative the other, as for example, the barrel rotatable within the casing, one part of which is provided with a plurality of plates arranged to be contained therein, as for ex-

ample, in the barrel, or to extend therefrom and engage the other part, which in the construction shown, is the casing. It will also be noted that the plates are substantially in different series, or that is, the lock is made up of a plurality of series of different plates, as, for example, the plates 19 may be considered one series, plates 10 a series, and plates 15 another series, which series may be further divided into sub-series, etc., the series to be employed depending upon the kind of key; also that the several series are independent from any other series, and the plates in any series are entirely independent from any other plates in that series, there being any desired number of plates in a series, any desired number of series, and with the plates assembled in any desired arrangement in the lock. The key may likewise be said to be made up with a plurality of series of independent cam faces, *i. e.*, a plurality of series of faces with a plurality of undulations or cam faces for each series, which are adapted to co-act and control the plates designed therefor, each face, independently controlling its respective series, or sub-series, irrespective of any other series. 70

Having thus described my invention, it is obvious that various immaterial modifications may be made in the same without departing from the spirit of my invention; hence I do not wish to be understood as limiting myself to the exact form, construction, arrangement or combination of parts herein shown and described, or uses mentioned. 75

What I claim as new and desire to secure by Letters Patent is:—

1. In a lock of the kind described and in combination, a suitable casing formed with a cylindrical bore with grooves on each side thereof, a cylindrical barrel rotatably mounted in said casing, and provided with an opening through the same from end to end, a key constructed with a plurality of pairs of irregular faces, the faces of each pair parallel and all substantially terminating in a point at the end of the key, said key longitudinally movable through the opening in said barrel, means at each end of the barrel for centering the key when inserted therein, and means co-acting with said key faces for locking said barrel against rotation within the casing, comprising a plurality of series of sheet metal plates extending through the barrel and transversely movable relative thereto in the same straight line to engage one or the other of the grooves in said casing, each plate being provided with a suitable keyway therethrough relatively larger than the cross sectional area of the key and contained within the periphery of the plate, the apertures of the plates in each series similarly formed, and each series having relatively different apertures than the other series, all of said plates 80

- of each series constructed to co-act with one of the pairs of said irregular faces substantially corresponding in contour with the aperture.
- 5 2. In a lock of the kind described and in combination, a casing member formed with a cylindrical bore extending lengthwise therethrough, with a groove on opposite sides thereof, a cylindrical barrel closely fitting the bore of said casing, and rotatably arranged therein, said barrel having an opening therethrough from end to end, and provided with a slot for a portion of its length, means carried by said member for engaging the casing at said grooves, comprising a plurality of plates arranged in the slots through said barrel and slideable therein in the same plane, the plates being provided with apertures therethrough, a key 70 75 movable in said cylindrical member and constructed on one side for engagement with a portion of said plates at the sides of the aperture therethrough, a portion of said plates being constructed at the sides of the apertures, for coöperation with said key, all of said plates having their ends formed to conform to the cylindrical face of the rotatable barrel when the key is in the lock, whereby the key and barrel may be rotated 80 85 90 95 100 105 110 115 120 125 130 135 140 145 150 155 160 165 170 175 180 185 190 195 200 205 210 215 220 225 230 an irregular form in a plurality of directions, and of a size to be inserted and forced through the apertures in the plates, whereby the plates will be engaged and moved into 5 alignment at their ends substantially flush with the face of the retaining member, a centering plate arranged at the outer end of said cylindrical member, and having a keyway therethrough, corresponding in contour, and of a size to substantially closely 10 fit the key, a key centering part at the other end of said cylindrical part, and an arm carried by the cylindrical member and projecting through the circumferential slot in said 15 casing, and a slidable lock bar constructed to engage said arm.

9. The combination in a key-actuated lock, of a substantially cylindrical casing offset on opposite sides and flanged at one end, 20 said casing formed with a cylindrical bore and internally grooved on opposite sides at said offsets, and circumferentially slotted at one side, a cylindrical barrel rotatably arranged within said casing and slotted 25 throughout a portion of its length from side to side, said cylindrical part having an opening therethrough at one end, a centering plate arranged at the front end of said

cylinder at the opening thereof, and provided with a keyway therethrough corresponding in contour and closely fitting the key, a plurality of substantially thin sheet metal, independently slidable plates arranged within the slot in said cylindrical member, said plates being of a length to be 30 entirely confined within the cylindrical part and of a width to closely fit the grooves in said casing, and each formed with an aperture therethrough, a suitably formed key having a plurality of parallel faces 35 constructed to engage said plates at the apertures therein and positively move the same in or out of engagement with the grooves in the casing, said cylinder provided with a lock bolt actuating and locking arm extending 40 through the circumferential slot in said casing, and a lock bar extending transversely of the barrel, constructed to engage said arm.

In testimony whereof, I have hereunto signed my name in the presence of two subscribing witnesses. 50

EMIL A. CHRISTOPH.
